CROSS HEAD

Henry E. Muchnic, Atchison, Kans., assignor to
 The Locomotive Finished Material Company,
 Atchison, Kans., a corporation of Kansas

Application December 31, 1938, Serial No. 248,630

2 Claims. (Cl. 287—20)

My invention relates to cross heads of steam engines and more particularly to cross heads employed on locomotives for transmitting the reciprocatory movements of the pistons of the cylinders to the crank-pins of the drive wheels through the medium of the main rods.

The invention has for its object the provision of a construction wherein the connection between the cross heads and the piston-stems or rods is obtained by means which will permit the connection to be easily effected and disconnection or disassembly to be as readily made in the event of repair or renewal.

In constructions as heretofore made, the piston rods are connected to the cross heads by means of keys which must be wedged or tightly driven into registering slots or openings in the piston rods and cross heads. These keys become to tightly wedged, as a result of the hammer blows, that at times it is extremely difficult to remove same.

Furthermore, the piston-rods of these prior structures, become so tightly wedged in the cross heads that it is impossible to "break" the joint or connection between the rods and the cross heads without applying heat to the cross heads. I am aware of the use of what are known as cross-head pullers for disconnecting the wedged piston-rods from the cross heads, but the use of such pullers is objectionable because the pullers fulcrum on a very weak portion of the cross head and often results in breaking or overstraining the back of the cross head before the piston-rod loosens and consequently necessitates repair or replacement of the cross head.

My invention is designed to obviate these difficulties; and although the fit or connection between the cross head and the piston-rod retains the principle of the key, my improved structure permits a much easier assembly as well as disassembly to be made; namely a structure wherein the use of keys is eliminated while at the same time providing an intimate interengaging connection between the cross heads and the piston-rods adapted to withstand the reciprocatory thrusts.

The above enumerated objects and the advantages inherent in the invention will all be readily comprehended from the following detailed description of the drawing wherein:

Figure 1 is a side elevation of my improved cross head with a portion of a piston rod connected thereto.

Figure 2 is an inverted plan view, with portions broken away and in section; the view being

taken on the line 2—2 of Figure 1 and looking in the direction of the arrows.

Figure 3 is a vertical sectional view taken on the line 3—3 of Figure 1 looking in the direction of the arrows.

Figure 4 is a sectional view taken on the line 4—4 of Figure 1 as indicated by the arrows.

My invention relates to cross heads and particularly to the type employed on locomotives and comprises the main body portion 10 consisting of the two vertically disposed and laterally spaced apart walls 11, 11, for slidably receiving the usual guide bars or slideways therebetween and preferably provided at the bottom with a reinforcing strap, a portion whereof is shown at 12; 13 while the side walls, intermediate of the tops and bottoms, are provided with the holes 13 for receiving the usual wrist-pin for connecting the main rod to the cross head.

The side walls 11, 11, at one end of the cross head, are connected together as shown at 14, see Figure 3, and this portion 14 is provided with an extension 15, disposed to one side of the longitudinal median line of the cross head. The extension 15 is enlarged or given arcuate formation, intermediate of its top and bottom and this enlarged or arcuate portion formed to constitute one half or part of a sleeve, the bore or socket whereof is adapted to receive the end of the piston-rod of which a portion is shown at 16. 30

The bore of this sleeve member 15 is shown provided with semi-circular grooves 17, see Figure 2, of any suitable number and preferably arranged in spaced relation lengthwise of the sleeve forming member 15.

The other wall of the piston-rod receiving socket or sleeve portion consists of a removable complementary member or cap 18 which is preferably coextensive with the length of the sleeve forming member 15, with its inner surface or 40 socket also provided with semi-circular grooves 19, which are coextensive or circumferentially aligned with the semi-circular grooves 17 in the body extension or sleeve forming member 15.

The side walls of the grooves 17 and 19 are 45 preferably tapered slightly as shown in Figure 2, to effect a firmer, non-vibrating relation with the preferably tapered annular collars or flanges 20 formed on the end of the piston-rod and spaced apart longitudinally, to provide multiple 50 points of attachment or interengaging relation between the cross head and the piston-rod.

The complementary sleeve forming member or cap 18 is shown secured to the socketed side of the extension or sleeve forming member 15 by a

plurality of bolts 21. In order, however, that the bolts 21 may not be subjected to or made to carry the piston-rod thrusts, I prefer to provide an interengaging relation between the cap 18 and the portion 15 which latter is preferably an integral part of the cross head. In the particular exemplification, this is accomplished by providing the cap 18 with lugs or extensions 22, while the cross head wall portion 14 and the lower end of the sleeve-forming member 15 are provided with cut-outs or recesses 23 adapted to receive the lugs 22. As is apparent from this construction, the cap holding bolts will not be subjected to the piston-rod thrusts, but, on the other hand, the portion of the thrusts encountered by the cap member will be transmitted through the lugs or extensions 22, 22 to the main body of the cross head.

In structures as at present employed, the connection between the piston-rod and the cross head is effected by means of wedge-keys driven through slots in the cross head and the piston-rod. In order to provide a secure connection, these wedge-keys must be tightly driven into place, which fact, at times makes it extremely difficult to remove these keys.

With my improved construction, the operative connection between the piston-rod and the cross head can be very readily made and a very firm or rigid connection provided; while on the other hand dissociation between the piston-rod and the cross head may be very quickly and easily made in the event of repair or replacement by simply removing the nuts on the bolts 21, which enables the cap member 18 with its lugs 22 to be moved laterally out of interengaging relation with the body of the cross head causing the

grooves in the cap member to be moved out of engagement with the annular flanges or collars 20 of the piston-rod and permitting the piston-rod to be released from the grooves in the integral portion of the cross head.

5

The exemplification shown is a practicable embodiment of the invention which has been described in terms employed for purposes of description and not as terms of limitation, as modifications are possible and may be made 10 without, however, departing from the spirit of my invention as expressed in the appended claims.

What I claim is:

1. A cross head of the character described 15 comprising a main body provided at one end with an extension socketed on one side; a complementary member provided with a socket on one side to match the socket of said extension; the extension and complementary member having 20 interengaging surfaces whereby thrusts encountered by the complementary member will be transmitted to the main body; and means whereby the complementary member is removably secured to the socketed side of said extension. 25

2. A cross head of the character described comprising a main body provided with a socketed portion and a shoulder adjacent the socketed portion; a complementary member formed to abut said shoulder and socketed on one face to 30 match the socketed portion of the main body to receive a piston rod, the body and said complementary member being provided with interengaging surfaces; and means whereby the complementary member is removably held in place. 35
